Fig. 3

Fig. 4

Fig. 5

Fig. 1 is a view in side elevation of a photophone showing my new design, the opposite side being substantially a mirror image thereof;

Fig. 2 is a view in front elevation of the same;

Fig. 3 is a view in rear elevation of the same;

Fig. 4 is a top plan view of the same; and

Fig. 5 is a bottom plan view of the same.

Portions of the drawing figures are diagonally lined to indicate transparencies as in the two upper symmetrical members of Fig. 2 and reflecting surfaces as in the larger lower member of Fig. 2, Fig. 3, and Fig. 4.

I claim:

The ornamental design for a photophone, substantially as shown and described.
